(57) **CLAIM**

The ornamental design for an artificial Christmas tree trunk,
as shown and described.

DESCRIPTION

FIG. 1 is a perspective view of my invention;

FIG. 2 is a front elevation view;

FIG. 3 is a rear elevation view;

FIG. 4 is a right side elevation view;

FIG. 5 is a left side elevation view;

FIG. 6 is a top plan view;

FIG. 7 is a bottom plan view; and,

FIG. 8 is a perspective view showing an application of the
invention.

The broken lines of FIGS. 1 through 8 form no part of the
claimed invention.
